RAILWAY TRAFFIC CONTROLLING APPARATUS

Frank H. Nicholson, Edgewood, and Harold W. Bryan, Wilkinsburg, Pa., assignors to The Union Switch & Signal Company, Swissvale, Pa., a corporation of Pennsylvania

Application November 24, 1933, Serial No. 699,540
Renewed November 15, 1934

10 Claims. (Cl. 246—34)

Our invention relates to railway traffic controlling apparatus, and more specifically to apparatus for providing broken down insulated rail joint protection in traffic governing systems which utilize coded rail current for controlling wayside and/or cab signals.

We will describe one form of railway traffic controlling apparatus embodying our invention, and will then point out the novel features thereof in claims.

The accompanying drawing is a diagrammatic view showing one form of apparatus embodying our invention as applied to a stretch of railway track equipped for wayside and cab signaling.

Referring to the drawing, the reference characters 1—2 and 2—3 designate two adjoining sections of a stretch of track over which traffic normally moves from left to right, in the direction of the arrow. Each track section is electrically insulated from adjoining sections by insulated rail joints, in the usual manner. Section 1—2 is normally supplied with coded rail current from a transformer T¹, and section 2—3 is similarly supplied with rail current from a transformer T². For purposes of illustration, the rail current will be assumed to be of the usual frequency code, comprising alternating current periodically varied at a frequency of 180, 120 or 80 impulses per minute, in accordance with traffic conditions in advance. The rail current is coded by a suitable code transmitter CT for each section, having the periodically operated contacts 180, 120, and 80, which furnish the 180, 120 and 80 code frequencies, respectively.

Considering section 2—3, the direct current code-following track relay TR², energized through the relay transformer RT² and rectifier R², periodically reverses the flow of direct current from a source B—C, in the primary winding of the decoding transformer DT², thereby inducing an alternating secondary voltage of a frequency corresponding to the code being followed by the track relay. The decoding relay H², energized through rectifier RH², is non-selective as to code and responds to operation of the track relay on any one of the 180, 120 or 80 code frequencies. Decoding relay E², however, is selective and will respond only to 120 code because of electrical tuning by means of the usual tuning unit DE², comprising a reactor, condenser and rectifier. Similarly, the decoding relay F² will respond only to 180 code because of the interposition of a similar unit DF², tuned to the 180 code. Since the tuning units DE² and DF² are well known, the elements comprising these units have not been shown in detail.

The protection relay LP² controls the application of the 120 and 180 code frequencies to the rear section 1—2, and is sufficiently slow releasing to bridge the operation of track relay TR².

on any one of the three codes. That is, as long as relay TR² is following code, relay LP² will be maintained energized over front contacts 4 and 5 of relays TR² and H², respectively. The indications of signal S² are selectively controlled by the group of relays H², LP², E² and F² in a manner which will be obvious from the drawing, and it is deemed unnecessary to trace the signal control circuits in detail.

We shall next explain the operation of the system as a whole. If at least two sections in advance of section 2—3 are unoccupied, 180 code will be supplied to section 2—3 from transformer T². Under this condition, if section 2—3 is also unoccupied, relay TR² will be following 180 code, and relays H², LP², and F² will all be energized. Consequently, 180 code will be supplied to the rear section 1—2 over a circuit which includes the following: one terminal BX of a source of current, front contact 6 of relay TR², front point of contact 7 of relay F², front contact 8 of relay LP², front point of contact 9 of relay H², and the winding of track transformer T¹, to the other terminal CX of the source. It should be noted that the above circuit does not include the 180 code contact of code transmitter CT², the 180 code for section 1—2 being produced through the periodic operation of contact 6 when relay TR² is following 180 code.

If but one section in advance of section 2—3 is unoccupied, relay TR² will be following 120 code, and relays H², LP², and E² will be energized. The rear section will again receive 180 code, but the circuit will now include: contact 180 of code transmitter CT², front point of contact 10 of relay E², back point of contact 7 of relay F², front contact 8 of relay LP², and front point of contact 9 of relay H². If the section in advance of section 2—3 is occupied, relay TR² will be following 80 code, and relays H² and LP² will be energized. Section 1—2 will, therefore, receive 120 code over a circuit which includes the following: contact 120 of transmitter CT², back point of contact 10 of relay E², back point of contact 7 of relay F², and the front contact 8 and front point of contact 9 of relays LP² and H², as before. If section 2—3 is occupied, section 1—2 will receive 80 code over a circuit which includes the 80 code contact of transmitter CT², and the back point of contact 9 of relay H².

From the foregoing description, it will be observed that relay LP² must always be energized before a code higher than 80 can be supplied to the rear section. Also, if section 2—3 is receiving 180 code, the only way in which the rear section can receive 180 code is over a code-following contact of the track relay TR². Therefore, should relay TR² fail to respond for 60

any reason, such for example as a train entering section 2-3 from a siding, or the reversal of a switch in the section, the shunting of relay TR² will cause an interruption in the supply of 180 code to the rear section 1-2.

If the rail joints between sections 2-3 and 1-2 break down at a time when these sections are supplied with 80 code and 120 code, respectively, relay TR² will have both 80 and 120 code in its windings and will operate erratically. If the energization of relay E² is excessive, this relay may pick up intermittently under this condition, resulting in a flashing indication of signal S². Ordinarily, unless relay H² is considerably over-energized, the erratic code resulting from the inter-action of the 80 and 120 codes will cause relay H² to release, whereupon 80 code will be supplied to the rear section over the back point of contact 9 of relay H². It has been found in practice that if the rail joints break down when sections 2-3 and 1-2 are supplied with 120 and 180 code, respectively, the erratic code resulting will fail to pick up relay F². Usually relay E² will also be released, thus preventing a false signal indication.

Let it next be assumed that while a train is occupying section 2-3, the rail joints between sections 2-3 and 1-2 break down, permitting 80 code current from the rear section to operate relay TR². Relay TR², in following 80 code, will cause relay H² to become energized, thus interrupting the 80 code at the back point of contact 9, whereupon relays TR² and H² will both become deenergized. This operation will repeat itself periodically, and will cause signal S² to display a flashing indication which provides a distinctive warning of the rail joint insulation failure. It is understood that the pickup time of relay LP² is made sufficiently long to prevent pick up of this relay under the above condition.

Under ordinary conditions, no code other than 80 can influence the track relay of an occupied section, with the rail joints broken down, because stepping up of the code to 120 or 180 is prevented at the 80 code stage. A different result may follow, however, if it be assumed that while sections 1-2 and 2-3 are being supplied with 180 code, the rail joints at location 2 break down and a train enters section 2-3 from a siding, particularly if it be assumed that sufficient 180 code energy passes over the rail joints from transformer T¹ to operate relay TR². Since, under the above condition, the energy for transformer T¹ and therefore for relay TR² is carried over the front contact 6, a momentary stick circuit over the front contacts 6, 7, 8 and 9 of relays TR², F², LP² and H² will become effective to supply steady energy to transformer T¹ and so to hold relay TR² picked up on steady energy, whereupon relays F², H², and LP² will release. Therefore, the stick circuit will be broken and the release of relay H² will cause 80 code to be applied to section 1-2, resulting in the sequence of alternate 80 code pickup and release operations and the flashing signal indication described above.

Let it next be assumed that the rail joints are broken down and a train enters section 2-3 from a siding at a time such that section 2-3 is receiving 120 code and section 1-2 is receiving 180 code. Under this condition, relays E², LP², and H² will be energized so that transformer

T¹ will be receiving 180 code over contact 180 of code transmitter CT², front contacts 10, 8, and 9 of the foregoing relays, and back contact 7 of relay F². However, should relay TR² begin to operate on 180 code passing over the joints from transformer T¹, relay F² will pick up, transferring the supply of energy from contact 180 of transmitter CT², to front contact 6 of relay TR², assuming for the moment that front contact 7 became closed during the time that front contact 6 was also closed. Relay TR² will now be held up over the stick circuit previously described until relay H² releases and causes 80 code to be supplied to transformer T¹, and causes a flashing indication to be displayed by signal S². Relay F² is sufficiently slow releasing to permit relay H² to release under this condition, in order to prevent 120 code from being applied to transformer T¹ and to insure that the flashing indication resulting from 80 code operation of relay TR² will be obtained.

If front contact 7 of relay F² closes at a time when contact 6 of relay TR² is open, the above-mentioned stick circuit will not be completed and relay TR² will remain deenergized for an interval, bringing about the release of relays F², H², and LP². As soon as relay H² releases, 80 code will be applied to section 1-2, and the flashing signal indication will again be produced.

If the rail joints break down and a train enters section 2-3 from a siding at a time when this section is receiving 80 code and the rear section 1-2 is receiving 120 code, then, should relay TR² follow the 120 code from the rear section, relay E² will pick up and will step up the code for the rear section to 180. The operation from this point on will be the same as previously described, that is, relay TR² will either be maintained energized or deenergized for a prolonged interval, according as front contact 7 of relay F² becomes closed at a time when contact 6 of relay TR² is open, respectively. In either case, the erratic 80 code will again be furnished to section 1-2 and signal S² will display a flashing indication.

From the foregoing description, it will be apparent that irrespective of the particular codes being effective in the adjoining track sections at the time when the rail joints break down and a dangerous traffic move occurs, the apparatus disclosed will provide protection by preventing a "clear" signal from being displayed, and by providing a distinctive indication as a warning of this particular type of failure. Although the frequency code has been used for purposes of illustration, it will be understood that the code may be of any suitable type, and may be either alternating or direct current.

Although we have herein shown and described only one form of railway traffic controlling apparatus embodying our invention, it is understood that various changes and modifications may be made therein within the scope of the appended claims without departing from the spirit and scope of our invention.

Having thus described our invention, what we claim is:

1. In combination, two adjoining sections of railway track, a source of coded current and a code-following track relay connected with the rails of one of said sections, a decoding relay responsive to code operation of said track relay, a slow acting relay controlled over a front contact of said track relay and a front contact of said decoding relay, and means including a con-

tact of said track relay and a contact of said slow acting relay for supplying rail current to the other of said two sections.

2. In combination, two adjoining sections of railway track, means for supplying coded rail current to one of said sections, a code-following track relay for said one section, a decoding relay which becomes energized in response to code operation of said track relay, a slow acting relay energized over a front contact of said track relay and a front contact of said decoding relay, and means including a front contact of said track relay and a front contact of said slow acting relay for supplying rail current to the other of said two sections.

3. In combination, two adjoining sections of railway track, means for supplying one of said sections with rail current of a first or of a second code in accordance with traffic conditions, a code-following track relay for said one section, a first and a second decoding relay responsive to code operation of said track relay on said first and said second code respectively, means including a back contact of said first decoding relay for at times supplying rail current to the other of said two sections, and means including a front contact of said track relay and a front contact of said second decoding relay for at other times supplying rail current to said other section.

4. In combination, two adjoining sections of railway track, means for supplying one of said sections with rail current of a first or of a second code in accordance with traffic conditions, a code-following track relay for said one section, a first decoding relay which becomes energized in response to operation of said track relay on either said first or said second code, a second decoding relay which becomes energized in response to operation of said track relay on said second code, means including a back contact of said first decoding relay for supplying rail current of said first code to the other of said two sections, and means including a front contact of said track relay and a front contact of said second decoding relay for supplying rail current of said second code to said other section.

5. In combination, two adjoining sections of railway track, means for supplying one of said sections with rail current of a first or of a second code in accordance with traffic conditions, a code following track relay for said one section, a first decoding relay which becomes energized in response to operation of said track relay on either said first or said second code, a second decoding relay which becomes energized in response to operation of said track relay on said second code, a slow acting relay controlled over a contact of said track relay and a front contact of said first decoding relay and capable of bridging the code operation of said track relay, means including a back contact of said first decoding relay for supplying rail current of said first code to the other of said two sections, and means controlled by said slow acting relay as well as said second decoding relay and including a front contact of said track relay for supplying rail current of said second code to said other section.

6. In combination, two adjoining sections of railway track, means for supplying one of said sections with rail current of a first or of a second code in accordance with traffic conditions, a code

following track relay for said one section, a first decoding relay which becomes energized in response to operation of said track relay on either said first or said second code, a second decoding relay which becomes energized in response to operation of said track relay on said second code, a slow acting relay energized over a front contact of said first track relay and a front contact of said first decoding relay and capable of bridging the code operation of said track relay, means including a back contact of said first decoding relay for supplying rail current of said first code to the other of said two sections; and means including a front contact of said first decoding relay, a front contact of said slow acting relay, a front contact of said second decoding relay, and a front contact of said track relay for supplying rail current of said second code to said other section.

7. In combination, two adjoining sections of railway track, means for supplying current of a first or of a second code to one of said sections in accordance with traffic conditions, a code following track relay for said one section, a coding device, means controlled by said track relay and effective when said one section is supplied with current of said first code for repeating the first code into said second section, and means effective when said one section is supplied with current of said second code for rendering said coding device effective to supply current of said first code to said other section.

8. In combination, two adjoining sections of railway track, means for supplying current of a first or of a second code to one of said sections in accordance with traffic conditions, a code following track relay for said one section, a coding device, means effective when said one section is supplied with current of said first code for repeating the first code into said second section over a contact of said track relay, and means effective when said one section is supplied with current of said second code for rendering said coding device effective to supply current of said first code to said other section.

9. In combination, two adjoining sections of railway track, means for supplying current of a first or of a second code to one of said sections, a code following relay controlled by current supplied to said one section, means controlled by said relay and effective when said one section is supplied with current of said first code for repeating the first code into said second section, and means exclusive of said relay and effective when said one section is supplied with current of said second code for supplying current of said first code to said other section.

10. In combination, two adjoining sections of railway track, means for supplying current of a first or of a second code to one of said sections, a code following relay controlled by current supplied to said one section, means effective when said one section is supplied with current of said first code for repeating the first code into said second section over a contact of said relay, and means exclusive of said contact and effective when said one section is supplied with current of said second code for supplying current of said first code to said other section.
